United States Patent

Des. 241,109
Patented Aug. 24, 1976

241,109

ROASTING PAN

Myron M. Levin, Highland Park, Ill., assignor to
E-Z Por Corporation, Niles, Ill.

Filed Mar. 26, 1975, Ser. No. 562,224

Term of patent 14 years

Int. Cl. D7—02

U.S. Cl. D7—85

Fig. 1.

Fig. 2.

Fig. 3.

Fig. 4.

Fig. 5.

FIG. 1 is a perspective view of a roasting pan showing my new design;

FIG. 2 is a top plan view thereof;

FIG. 3 is a side elevational view thereof;

FIG. 4 is a plan view thereof taken from the underside of the roasting pan; and

FIG. 5 is an end elevational view thereof.

I claim:

The ornamental design for a roasting pan, as shown.
